[57] CLAIM

The ornamental design for a telephone handset housing, as shown and described.

DESCRIPTION

FIG. 1 is a front, top, and right side perspective view showing my new design for a telephone handset housing in full lines, with the broken line matter being for illustrative purposes only and forming no part of the claimed design;

FIG. 2 is a left elevational view thereof in full lines, with the broken line matter being for illustrative purposes only and forming no part of the claimed design; and,

FIG. 3 is a rear elevational view thereof in full lines, with the broken line matter being for illustrative purposes only and forming no part of the claimed design.

FIG. 1

FIG. 3

FIG. 2
